UNITED STATES PATENT OFFICE.

LEANDER J. McCORMICK, WM. R. BAKER, AND L. ERPELDING, OF CHICAGO,
ILL., ASSIGNORS TO C. H. McCORMICK & BROTHER, OF SAME PLACE.

IMPROVEMENT IN HARVESTERS.

Specification forming part of Letters Patent No. 83,520, dated October 27, 1868.

To all whom it may concern:

Be it known that we, LEANDER J. McCORMICK, WILLIAM R. BAKER, and LAMBERT ERPELDING, all of Chicago, in the county of Cook and State of Illinois, have invented certain new and useful Improvements in Harvesters, of which the following is a full, clear, and exact description, reference being had to the accompanying drawings, which make part of this specification, and in which—

Figure 1 represents a plan or top view of a harvester to which our improvements are applied. Fig. 2 represents a view, in elevation, of the inner or grain side of the same. Fig. 3 is a diagram, showing the operation of the devices for lifting the outer end of the finger-beam. Fig. 4 is a front view of the counter-shaft and shipping mechanism detached; Fig. 5, a section through the roller which supports the heel of the finger-beam. Figs. 6 and 7 show the details of the device for adjusting the tongue.

Our invention relates to that class of harvesters known as two-wheeled hinged-joint machines; and our invention consists in certain novel devices, hereinafter fully described.

In the accompanying drawings, our improvements are shown as adapted to a rear-cut machine, such as that shown in the patent of McCormick and Erpelding, dated January 15, 1867, and numbered 61,228.

A stout main frame, A, is mounted on two driving and supporting wheels, B, turning loosely on an axle, b. A supplementary frame, C, is pivoted to play vertically in proper bearings beneath the main frame, in front of the main axle, and coincident with the counter-shaft D. The inner longitudinal frame-piece C' extends backward beyond the other parts of the supplementary frame, and supports a stirrup, E, which extends below the frame, as shown in Figs. 2 and 3. The finger-beam G is provided with a suitable cutting apparatus, and rigidly secured to a shoe, H, which is pivoted behind the finger-beam to a swiveling-pin, h, Fig. 1, passing horizontally through the stirrup E. The front end of the shoe is pivoted to an arched coupling-bar, F, which extends up over the supplementary frame, and is pivoted near its outer rear corner. These devices allow the finger-beam to rock

axially, and to rise and fall at either end, to conform to undulations of the ground, as is well understood. The rear end of the shoe terminates in an arched recess, i, which forms a shield or covering for an oval roller, I, which turns in bearings in the shoe. The eye of this roller is made larger than the axle which goes through it, and has a hollow wooden plug or bushing, i', inserted in it, as shown in Fig. 5.

By this mode of construction we insure a snug fit, and prevent the roller from wabbling in its bearings, thus holding the finger-beam steady and at a uniform height from the ground.

A lever, J, is pivoted on the swivel eyebolt or pin h, and connected with the arched brace F, under which it passes. This lever extends within easy reach of the driver, (who sits on the main frame,) and is provided with a spring-detent, j, and sector-rack j', of the usual form. This lever serves to rock the finger-beam axially, and to hold the guards at any desired inclination to the ground. A lifting-lever, K, is pivoted to play vertically in a bracket, k, on the side of the main frame, and is also controlled by the driver. A link, k', connects this lever with a rocking-lever, K', the other end of which is connected with a dog or bent lever, L, vibrating on the swivel-pin h, and with its toe acting on a horn, l, Fig. 1, projecting from the shoe H.

The first effect of lifting this lever K is to depress the toe and horn l, and thus lift the divider end of the finger-beam, as shown in Fig. 3. The continued upward movement of lever K lifts the supplementary frame and the heel end of the finger-beam entirely from the ground, as shown in Fig. 2.

The stirrup E, it will be observed, extends much lower than in the former patent of January 15, 1867, above mentioned, and the swivel-pin h passes through it parallel to the finger-beam, instead of transversely, as in that patent. The locking-lever in that patent was arranged parallel with the finger-beam, and merely prevented the divider end from descending below the heel of the finger-beam, but could not prevent it from descending below a horizontal line.

In the present machine, on the contrary, the lever L is arranged transversely to the

finger-beam, and acts on the horn *l*, so as not only to prevent the divider from falling below a horizontal plane; but to elevate the divider end of the cutting apparatus, at the will of the driver, which, in practice, we have found a useful improvement.

The tongue *M* is pivoted in a socket, *m*, with diverging sides, by a vertical bolt, *m*², as shown in Fig. 1, to allow a slight degree of lateral play. A corrugated bracket, *m*², is secured to the front cross-beam of the main frame, and has a ledge, *m*³, projecting from it. A corresponding corrugated socket, *m*⁴, is secured to this ledge by a vertical bolt passing through the tongue, and through a slot in the ledge, which may thus be adjusted laterally, and locked by the corrugations to regulate the angle of the tongue to the frame, and thus counteract side draft, and also cut a full swath on side-hills.

Internally-gearred spur-wheels *N* on the main wheels drive corresponding pinions *n* on the counter-shaft, with which they are connected by the usual backing-ratchets. A bevel-wheel, *O*, on this shaft drives a corresponding pinion, *o*, on the crank-shaft *P*, which drives the cutters by a crank and pitman in the usual way.

In order to vary the speed of the cutters, when desired, we secure the pinion *o* on its shaft by a nut, *o'*, and feather and key, Fig. 1, which are easily removable, so as to allow pinions of different sizes to be substituted one for the other.

In order to accommodate the bevel-wheel *O* to this change, it is provided with a collar, which slides endwise on the counter-shaft, and is held in place by a set-screw. A sliding clutch, *R*, of well-known form, serves to throw the bevel-wheel into and out of gearing. The shipper *r* must, however, move farther in one direction when a larger pinion is used on the crank-shaft. In order to hold it in either position, we form three notches in the catch-plate *s*, which notches are so arranged as to accommodate the change of pinions.

In order to protect the gearing from dirt, grit, &c., we employ shields *S*, extending from the main frame over the counter-shaft, and embracing the spur-pinions *n* within the periphery of the driving-wheels.

The operation of the mechanism is so obvious as to require no description.

We are aware that the gearing of harvesters has been protected by covering it in various

ways; and do not, therefore, claim anything more than our specific devices for attaining this result.

We are also aware that the speed of the gearing has been varied by using two pinions on the crank-shaft in combination with two gear-wheels on the driving-shaft.

We are also aware that the speed has been varied by moving the shaft sidewise in its bearings to accommodate pinions of different sizes; and do not claim these modes of varying the speed; but we know of no device previous to ours of a bevel-wheel sliding on a counter-shaft to accommodate pinions of different sizes, applied one at a time on a crank-shaft.

What we claim as our invention, and desire to secure by Letters Patent, is—

1. The combination, substantially as set forth, in a two-wheeled harvester, of a tongue, with its rear end pivoted, so that the tongue can play laterally in a socket over the main axle, a corrugated laterally-slotted bracket on the front of the main frame, a correspondingly corrugated socket on the tongue, and a vertical clamping-bolt connecting the socket and bracket, whereby the angle of the tongue to the line of draft can be varied at pleasure.
2. The shields *S*, constructed as described, attached to the main frame, and inclosing the counter-shaft, the pinions which drive it, and the backing-ratchets, for the purpose set forth.
3. The arrangement, as set forth, for joint operation of the counter-shaft, the adjustable bevel-gear *O*, and its sliding clutch with the nut and removable pinion on the front end of the crank-shaft, whereby we vary the speed of the cutters by using a single gear-wheel on the counter-shaft without moving either shaft.
4. The arrangement, as described, for joint operation, of the finger-beam, the shoe, and the stirrup with the horn *l* and dog *L*, whereby we lift the divider end of the finger-beam first in raising the cutters.
5. The combination, as set forth, of the shoe *H* and arched shield *i* with the roller, provided with wooden bushing.

In testimony whereof we have hereunto subscribed our names.

L. J. McCORMICK.
WM. R. BAKER.
L. ERPELDING.
